(57) **CLAIM**

The ornamental design for a safety fence as shown and described.

DESCRIPTION

1.1: Perspective

1.2: Perspective

1.3: Front

1.4: Back

1.5: Left

1.6: Right

1.7: Top

1.8: Bottom

The product of the design is a safety fence installed around picking equipment, etc., in a warehouse, for example, to prevent contact between workers, etc., and the equipment. In the reproductions, the broken lines illustrate unclaimed portions of the article and form no part of the claimed design. The dash-dot broken lines illustrate only the boundary between the claimed design and the other portions of the article. The dot-solid long-dot lines illustrate transparent material.
